CLAIM

The ornamental design for a beverage container holder/
insulator, as shown and described.

DESCRIPTION

FIG. 1 is a perspective view of a beverage container holder/
insulator of the present invention, showing my new design;

FIG. 2 is a side elevation view thereof;

FIG. 3 is a top plan view thereof;

FIG. 4 is a side elevation view of an alternate embodiment
of FIG. 1, the difference being an elongated version; and,

FIG. 5 is a bottom plan view thereof.
